SMOKE OBSERVATION MECHANISM

John F. Horvath, Milwaukee, Wis., assignor to Cleaver-Brooks Company, a corporation of Wisconsin

Application December 23, 1953, Serial No. 399,935

8 Claims. (Cl. 116—114)

This invention relates to a smoke observation mechanism and more particularly to a means for observing smoke in a stack in order to determine the characteristics of the fire producing the smoke.

Boilers have for some time been equipped with various burner mechanisms using light oil, heavy oil, and gas as the fuel. The condition of the burner and the tubes in the boiler may be somewhat indicated by the appearance of the smoke in the stack leaving the boiler. In the past, such stacks have been provided with a hole cut in one side covered by a curved plate merely placed over the hole. The plate has been mounted on a pivot pin and its own weight has been relied upon to hold it over the hole to prevent the leakage of gas from the stack. In forced draft furnaces, the smoke ordinarily is passing through the stack with sufficient speed to permit the opening of the hole for smoke observation with the use of a flashlight or some other artificial illumination.

In the present invention, a mechanism is provided which seals the observation passage from any leakage when not in use and which has the advantage of being usable without the need of artificial illumination.

The principal object of the present invention is to provide a mechanism for opening an observing passage in a smokestack and at other times sealing such passage.

Another object is to provide such a mechanism which may be opened and closed from one side of the stack.

A further object is to provide such a mechanism which is not affected by corrosive gases in the stack itself, and

A further object is to provide a mechanism which may be easily manufactured and installed on a stack.

Other objects, features, and advantages of the present invention will be apparent from the following description taken in conjunction with a particular embodiment illustrated in the accompanying drawings in which:

Figure 1 is a fragmentary side elevational view of the front end of a boiler unit showing the smoke observation mechanism mounted on the stack of the unit;

Figure 2 is a fragmentary front elevational view of the mechanism taken substantially along line 2—2 in Figure 1;

Figure 3 is a fragmentary vertical sectional view showing a portion of the mechanism in detail and taken substantially along line 3—3 in Figure 1;

Figure 4 is a horizontal sectional view through the mechanism taken substantially along line 4—4 in Figure 2; and

Figures 5 and 6 are fragmentary side elevational views illustrating the mechanism in open and closed positions respectively.

The particular boiler structure illustrated in part in Figure 1 includes a boiler shell 10 mounted on skids 11 and having a front door 12 upon which is mounted a burner housing 13 and a fan motor 14 for supplying air to the burner. An air intake 15 conducts air to the fan which is run directly on the shaft of the motor 14. The boiler includes a number of fire tubes, and in the particular embodiment shown, is a four-pass forced draft

furnace. The fuel may be light oil, heavy oil, or gas at the option of the operator. The combustion products pass through the fire tubes and finally exhaust through the stack stub 16. This stub is provided with an upper flange 17 for connection with the stack of the building wherein the boiler is used. The structure of the boiler itself is more completely set out in the copending application of Messrs. Cleaver, Loebel and Horvath, Ser. No. 403,286, filed January 11, 1954. The present invention is concerned only with the smoke observation mechanism for the stack 16 and the boiler is illustrated for purposes of adding the environment.

The smoke observation mechanism is intended to require a minimum of upkeep and repair and to this end the parts are protected from the corrosive effect of the combustion products in the stack. It is also intended that the mechanism be operable for observing the flow of smoke in the stack without the use of artificial light. The mechanism itself includes a pair of short pipe nipples 18, each mounted in an appropriately cut hole 19 in the sides of the stack at diametrically opposite positions. The nipples are welded in place, care being exercised to align them along the same axis. A deviation from true alignment may be tolerated as the nipples serve only the purposes of defining the passage and providing a seat for other mechanisms to be described. Ordinarily the smoke observation passage defined by the nipples 18 may be horizontal. On larger boiler units, the stack may be comparatively high from the ground or floor so that the passage may be inclined to the horizontal to permit easy viewing.

The sealing mechanism for the observation passage comprises primarily a plate 20 approximately oval-shaped, with an outer edge 21 generally circular in form so as to fit over and close the adjacent nipple 18. Each plate is provided with a square opening 22 in the narrow portion for the reception of a square shaft or rod 23. This rod supports the plate in part and provides a means for swinging the plate laterally of the nipple to expose the smoke observation passage to view.

The rod is protected from the corrosive effect of combustion products by a tubular elongated sleeve 24 welded into the stack and passing through the stack generally parallel and to one side of the nipples 18. The end portions 25 of the sleeve extend outwardly from the stack and the rod 23 extends out of each end of the sleeve. The plate 20 is mounted on the rod between the end of the sleeve 24 and the shank 26 of a handle member 27. The fit is loose so that the plate may have some longitudinal movement on the rod and also some canting movement permitted by the difference in size of the square opening 22 and the size of the square rod 23. The handle 27 is secured to the rod by a pair of set screws 28 so that turning of the handle moves the rod and simultaneously swings the plate 20 relative to the nipples 18.

Means are provided to insure a tight closure of the observation passage when not in use. Herein, this means comprises a compression spring 29 mounted about a boss 30 on the handle member 27 and pressing against the plate 20. The plate is flat and the outer end of the nipple 18 is machined to present a planar end which may be sealed by the plate. There is no particular tendency for the spring to move out of alignment since both the handle and plate are mounted on the rod and turn with the rod. One handle 27 may be provided with an outwardly extending handle portion 31 or, in the alternative, both handle members may be so constructed. Ordinarily the observation passage will be opened from one side of the stack and the extension 31 on the handle member should be placed on this side.

A pin stop member 32 is provided on the inside of one of the plates 20 so that it may bear against the inside of

one nipple 18, as illustrated in Figure 5, to limit the lateral swinging of the plates 20 relative to the nipples. A small portion of the passage defined by the nipples is closed by the edge portion 33 of the plates, however, the amount that the plate remains over the passage is very small compared with the size of the passage itself. This small amount of ever-present covering of the passage does not impair the operator's ability to see the smoke in the stack.

It will be noted from the structure that each of the plates 20 is supported on the nipples under the action of the compression spring. The nipples can be out of alignment and yet the plates will be able to fit on the outer end thereof due to the looseness of the mounting between the plates and square rod.

The foregoing detailed description has been given for clearness of understanding only, and no unnecessary limitations should be understood therefrom, for some modifications will be obvious to those skilled in the art.

I claim:

1. A smoke observation mechanism for a stack, comprising: a pair of aligned nipples one on either side of a stack to provide a substantially straight light passage through the stack; a swingably mounted plate slidable over the exposed end of each nipple for opening and closing the light passage, means yieldingly urging the plates into seating engagement with the nipples, a rotatable rod supporting both of said plates for swinging movement upon rotation of the rod, and handle means on the rod permitting manual opening and closing of the passage from one side of the stack.

2. A smoke observation mechanism for a stack, comprising: a pair of aligned nipples one on either side of a stack to provide a substantially straight light passage through the stack; a mounting rod extending through the stack beside said nipples; a plate secured to each end portion of the rod in position to cover the adjacent nipple, said plates being yieldingly urged into tight engagement with the nipples and secured to the rod for swinging movement laterally of the nipples upon turning of the rod on its axis and handle means secured to the rod.

3. A smoke observation mechanism for a stack, comprising: a pair of aligned nipples one on either side of a stack to provide a substantially straight light passage through the stack; a sleeve extending through the stack generally parallel to the nipples; a rod extending loosely through the sleeve and protruding from each end; a handle on the rod; a plate mounted on each protruding rod portion for covering the adjacent nipple, each plate having limited movement relative to the rod and being secured for turning with the rod; and means yieldingly urging each plate member toward the adjacent nipple to provide a tight covering of the light passage.

4. A smoke observation window for a stack, comprising: aligned nipples one on either side of a stack to provide a substantially straight light passage through the

stack; a rod extending through the stack adjacent the nipples and generally parallel to the light passage; a handle member secured to each end of the rod and extending outwardly over the adjacent nipple; a generally flat plate mounted on the rod between each handle member and adjacent nipple and having a size to cover the nipple, said plate being slidably mounted on the rod and secured against rotation relative to the rod so as to turn therewith; and a spring member between each handle and adjacent plate urging the plate into sealing contact with the nipple while permitting movement of both plates off the nipples by manual turning of the rod from either side of the stack.

5. A smoke observation window as specified in claim 4 in which at least one plate has a stop lug projecting inwardly of the adjacent nipple to engage the nipple limiting movement of the plates laterally of the nipples.

6. A smoke observation window as specified in claim 4 wherein a sleeve extends through the stack and carries said rod, the sleeve being joined to the stack in gas-tight relation.

7. A smoke observation window as specified in claim 4 wherein a sleeve extends through the stack and carries said rod, the sleeve being joined to the stack in gas-tight relation, said plates each having limited movement axially of the rod between the end of the sleeve and the adjacent handle member.

8. A smoke observation mechanism for a stack, comprising: a pair of oppositely arranged nipples each positioned in a side of a smoke stack in gas-tight relation to provide a straight observation passage through the interior of the stack, each nipple having an outer planar end, and means for closing and opening the nipples from one side of the stack including a sleeve member extending continuously through the stack generally parallel to said observation passage and beside the nipples, an elongated rod extending through the sleeve member and protruding from each end of the sleeve, a cover plate mounted on the rod for limited axial movement thereon at each end in position to cover the outer planar end of the nipple, a handle member tightly secured to each end of the rod and having a portion extending outwardly over the adjacent cover member, and a compression spring member between the cover member and handle member yieldingly urging the cover member into seating position on the nipple, said cover members being secured to the rod for sliding movement away from covering relation upon turning of the rod within the sleeve with either handle member.
